Specification for Design.

Patented Oct. 26, 1915.

Application filed April 20, 1914. Serial No. 833,326. Term of patent 7 years.

To all whom it may concern:

Be it known that I, ANDREW WILSON, a citizen of the United States, residing at Berkeley, in the county of Alameda and State of California, have invented a new, original, and ornamental Design for Kitchen-Indicators, of which the following is a specification.

Referring to the accompanying drawing—the figure is a plan view of a kitchen-indicator, showing my new design.

Copies of this patent may be obtained for five cents each, by addressing the "Commissioner of Patents, Washington, D. C."

I claim:—

The ornamental design for a kitchen-indicator, as shown.

In testimony whereof I have signed my name to this specification in the presence of two subscribing witnesses.

ANDREW WILSON.
